UNITED STATES PATENT OFFICE.

JOHN E. JOHNSON, OF CHICAGO, ILLINOIS, ASSIGNOR TO SPEEDAUMAT ADDRESSING MACHINERY, INCORPORATED, OF CHICAGO, ILLINOIS, A CORPORATION OF DELAWARE.

SELECTOR-DISCHARGE MECHANISM.

Application filed August 7, 1922. Serial No. 580,003.

My invention relates to attachments for printing machines and it has special reference to attachments for machines employing address printing plates and which may be 5 of any of the usual types, such as wrapper addressing machines, strip addressing machines, mailing machines and the like. More particularly my invention relates to attachments of the character indicated in 10 which the address printing plates delivered from an addressing or mailing machine are automatically selected and segregated in accordance with the expiring date of the subscriptions that are represented by the separate address plates ejected from the addressing machine.

The mechanism or attachment of my present invention is applied to addressing or mailing machines which employ metallic address printing plates or address mats of a particular design. It is highly desirable to segregate these address printing plates as they are delivered from the addressing or mailing machine in accordance with the 20 expiring subscriptions as soon as the last newspaper or periodical which is forwarded thereunder has been printed.

It is an object, therefore, of my present invention to provide a selector attachment to 30 be applied to addressing, mailing or printing machines of the character described, which will be simple and economical to construct and will serve most effectively to automatically select the address printing plates of a predetermined class as, for example, those address printing plates representing expiring subscriptions and, thereafter, to segregate such selected address printing plates from the remaining address printing plates which may be utilized again. By means of my present invention, the address printing plates of expiring subscriptions are automatically collected within a suitable receptacle or galley and are thus 40 45 permanently separated from the other address printing plates which are to be utilized again in the addressing or mailing machine.

Further objects and advantages of my invention will be apparent after reference is 50 had to the following description and the accompanying drawings, in which—

Figure 1 is a side view in elevation of a form of my present invention showing the same attached to the discharge end of an addressing or mailing machine;

Fig. 2 is an end view of the machine of Fig. 1;

Fig. 3 is a view, partially in elevation and partially in section, taken along the plane 3—3 of Fig. 2;

Figs. 4, 5, and 6 are sectional views, respectively, taken along the lines 4—4, 5—5 and 6—6 of Fig. 1;

Fig. 7 is a sectional view taken along the line 7—7 of Fig. 6;

Fig. 8 is a sectional detail view taken along the line 8—8 of Fig. 1;

Fig. 9 is a view similar to that of Fig. 1 but showing a different operating position than that illustrated in Fig. 1;

*Fig. 10 is a plan view of an address printing plate of the type adapted for use in the machine of my present invention; and

Fig. 11 is an end view of the address plate of Fig. 10.

Before explaining the operation of the mechanism of my present invention, I will first explain its mechanical construction which will then readily permit of an understanding of the operation of my invention. Throughout the various figures of the drawings, the same reference characters are employed to designate corresponding elements.

Referring to the drawings, the end frame of an addressing machine or mailing machine to which the attachment of my present invention may be secured is represented by the reference character A. A main shaft 28 of the addressing machine projects through the frame A and by means of this shaft 28 power is available for operating my attachment. Address printing plates or address mats 12 and 12^a are shown as being ejected from the discharge end of the addressing or mailing machine. These address mats are advanced to the right in Figure 1 and into operative position in my selector attachment by means of a continuously reciprocating member 71 (Figure 3) which is applied to all addressing or mailing machines and is well known in the art. As shown in Figure 3, the reciprocating member 71 is provided

with pivoted pawls 80 which engage the address mats at their rear edges to advance them along the center rail 81 and the guide rails 66, as shown in Figure 4. The reciprocating member 71 operates through a range equal to the longitudinal dimension of the address mats and, therefore, each time that the reciprocating member 71 moves to the right in Figure 1 or to the left in Figure 3, an address mat, such as 12^a, is advanced forwardly a distance equal to its length. It is, therefore, obvious that a continuous supply of address mats, as they are ejected from the addressing or mailing machine, are advanced one by one by means of the reciprocating member 71 and the pawls 80 into operative relation with my selector mechanism. As mentioned above, the mechanism for feeding the address mats such as 12 and 12^a, forms no part of my invention since this mechanism is well known in the art. In connection with my present invention I have shown the feeding mechanism of the character described in 25 U. S. Patent No. 1,281,014 to Huneke.

My selector mechanism operates upon the address mats as they are delivered from the addressing machine and automatically selects those address mats of expiring subscription and then segregates such selected mats from the other address mats so as to ensure that a subscriber of the periodical or newspaper will not receive the periodical after his subscription has expired.

35 A cam 53, as shown in Figure 6, is mounted upon the main power shaft 28 and to the left of the main frame A of the addressing machine, as shown in Figure 1. The cam 53 is adapted to actuate a lever 33 that is pivoted at 32^a in a bracket 32 which is secured to one of the guide rails 66 of the addressing machine. The other arm 30 of the lever 33 serves as a supporting platform for a plurality of selector needles 29 that are retained in openings formed in a selector block 37. The lever arm 30 is also provided with a projection 30^a upon which is mounted an actuating member 32 for the electrical contact members 33^a.

50 The main shaft 28, at its outer end, is provided with a spiral pinion 27 which meshes with a spiral gear 26 mounted upon a rotatable shaft 24 and is journaled, as shown in Figure 2, in bearings 25. The bearings 25 are supported upon a mounting plate 39 which is bolted to the main frame A of the addressing machine. The shaft 28 is constantly rotating during the operation of the addressing machine and, as a consequence, the shaft 24, in turn, rotates. Upon the shaft 24 there is mounted a cam member 16^a and a cam member 45, as shown in Figure 8. The cam member 16^a, having a cam guide way 16 formed therein, is keyed to the shaft 24 by

means of a key 16^b. The cam member 45 is rotatably mounted upon the shaft 24. As shown in Figure 3 the guide way 16 has a sharply curved portion 16^c and two reversibly curved portions 16^b. The cam roller 17 is received in the cam guide way 16 and is connected to one end of a lever 18 that rocks a rotatably mounted shaft 19 which, in turn, is journaled in bearings 20, Figure 2, that are mounted upon a laterally projecting bracket arm 20^a which is integrally formed upon the mounting plate 39.

The second cam 45, which is in the nature of a segmental cam, is adapted to engage a roller 46, Figure 9, which is connected to one extremity 47 of a curved lever arm 48 that is pivotally secured at 49 to the lever arm 18. The curved lever arm 48 is connected at its end 50 by means of a link 51 to an address mat packing arm 15.

The address mat packing arm 15, as shown in Figure 3, is secured to the shaft 19 which is oscillated by means of the lever 18. Since the cam 16^a continuously revolves with the rotation of the shaft 28, the lever arm 18, which is actuated by the cam 16^a, imparts a continuously oscillating motion to the address mat packing arm 15. Under normal conditions, therefore, the address mat packing arm 15 oscillates uniformly through a relatively small arc but the movement of the packing arm 15 may be modified by means of the lever 48 which is actuated through the agency of the cam 45. Movement is imparted to the cam 45, as will be hereinafter explained, when a spring-pressed pin 43 of Figure 8 projects into a recess 44 formed in the cam member 16^a. The spring-pressed pin 43 is housed in the cam member 45 and is actuated by means of a compression spring 42 when a clutch block 40 secured on the end 41 of a lever 36, Figures 1 and 2, is withdrawn from the annular groove 55, formed in the cam member 45. When the clutch block 40 is withdrawn from the annular recess 55, the spring-pressed pin 43 projects into the recess 44 and thereby interlocks the cam 45 with the cam 16^a.

These two cam members, therefore, will now rotate in unison with the shaft 24. The cam 45 is also provided with a braking surface 59 whereupon a friction brake-shoe 58 continuously rests, as shown in Figure 1. Therefore, when the cam member 45 becomes disengaged from the cam member 16^a, the brake shoe 58, being pressed against the braking surface 59 of the cam member 45, will hold the latter stationary and against rotation.

Those address printing mats employed in the addressing machine, and which are subsequently submitted to the selector mechanism of my present invention in order to segregate those mats of expiring subscriptions, are illustrated in Figures 10 and 11. These address mats are formed of metallic

plates, preferably zinc, and are of rectangular form having parallel longitudinal integral ribs 100 and 101 formed on one face of said plate and spaced from its edges. Integral type 102, constituting the name and address or other information of the subscriber, is struck up on the same face of the plate between the longitudinal ribs 100 and 101 and is slightly higher than the ribs. The edges of the plate are bent over as illustrated and serve as means for guiding the address mats under guide ways 66^a that are attached to the guide rails 66 over the selector block 37, as shown in Figure 6.

Notches 103 and 104 are cut in the ends of the address plate adjacent to the lower longitudinal edge. These guide ways 103 and 104 serve to hold the address mats in the receptacles or receiving galleys, as will be hereinafter explained. The address mats are also provided with integrally formed bosses 105, 106 and 107 which project from the face of the plate on the same side as the type.

The bosses 105, 106 and 107 are spaced from each other and from the edges of the plate in accordance with a code which dictates the arrangement for designating the calendar dates of expiring subscriptions. In other words, the relative location and spacing of these bosses 105, 106 and 107 are dependent upon the date upon which the subscription of this particular subscriber expires. Now, assume that on a particular date all address mats of the subscribers whose subscriptions expire on this date are to be automatically segregated from the total quantity of mats ejected from the addressing machine. Therefore the selector needles 29 will be positioned in such holes formed in the selector block 37 that all mats having the properly positioned bosses 105, 106 and 107 correspondingly located are to be separated from the quantity of mats delivered from the addressing machine. As explained in connection with Figure 6, the three selector needles 29 are supported upon the arm 30, which forms a part of the lever 33. When the three pins 29 are received in the selective bosses formed in the address mats, the contact actuator 32, likewise mounted upon the lever 33, is permitted to engage the two opposed and spaced contact members 33^a, as shown in Figures 6 and 7 since the lever arm 30 may then move through its full range of travel. When the contact members 33^a are in engagement an electrical circuit is connected through the leads 108 and 109 which serves to energize the electromagnet 34 of Figures 1, 2, 3 and 9.

In Figure 1, the electromagnet 34 is shown as being deenergized and, as a consequence, the armature 35 and lever 36 occupy the positions wherein the clutch

block 40 of Figure 8 is received in the annular recess 55 of the cam 45. However, when the contact members 33^a are in engagement, the electromagnet 34 attracts the armature 35 and, therefore, causes the lever 36 to take the position shown in Figure 9. As a result, the clutch block 40 is withdrawn from the annular recess 55 of cam 45, and, as hereinbefore explained, the cams 16^a and 45 are then operatively connected to each other through the spring-pressed pin 43.

When the cam 45 rotates in unison with the cam 16^a upon the shaft 24, the cam roller 46 actuates the lever 48 and the link 51, thereby lowering the tamping foot 15^c, Figure 3, of the tamping arm 15. In this circumstance, the tamping foot 15^c occupies its lowermost position, as shown in Figure 9 and, therefore, the address mats 12 and 12^a, as they are fed adjacent to the tamping foot 15^c, are received upon its top surface. The address mats 12^a and 12 are moved in succession above the selector mechanism, the address mat 12^a being forced from its position above the selector mechanism by the next succeeding address mat 12 which takes the position above the selector mechanism as the address mat 12^a is forced into alignment with the receptacles 13 and 14. Since the tamping arm 15 is continuously oscillated the address mats received on its top surface will on subsequent upward movement of the tamping foot 15^c be forced upwardly into the upper receptacle 14 and thus segregated from the quantity of address mats ejected from the addressing machine.

It is to be understood, of course, that the electromagnet 34 is energized only when address mats having a predetermined arrangement of selective bosses thereupon pass over the selector block 37 of Figure 3. Again, the cam member 45 only rotates upon the shaft 24 when the electromagnets 34 are energized. In turn, the lever 48 is actuated only when the cam 45 is rotated and, therefore, the tamping foot 15^c occupies its lowermost position only when those address mats of expiring subscriptions are to be received on its upper face so that they may subsequently be injected into the upper receptacle 14.

The selector block 37 is provided with a plurality of spaced openings in which the selector pins 29 may be positioned and the address mats are provided with a series of markings or symbols, as shown in Figure 10, which, when the address mats are directly above the selector block 37, register with the openings in the block. The bosses 105, 106 and 107 are struck up on the address mats in accordance with a code which, on a certain calendar date representing the date of the expiring subscription, may be

designated on the address mat by the proper location of the selective bosses over these symbols. It is to be understood that the position of the selector needles 29, in the 5 various openings, may be varied at will and arranged to accord with the particular code designation representing the predetermined expiring date of subscription.

In the event that address mats pass over 10 the selector block 37 which are provided with selective bosses that do not admit of the closing of the electrical circuit through the electromagnet 34 and through mechanism of Figures 6 and 7, the cam 45 will then 15 be held against rotation by means of the friction brake 58 which engages the brake surface 59 on the cam member 45. The cam 16^a will then be the only one rotating with the shaft 24 and, consequently, the 20 packing arm 15 will partake of its normal oscillatory motion which constitutes an oscillation through a relatively small arc. Such address plates as do not permit of the closing of the electric circuit through 25 the electromagnets 34 are fed over the mat center rail 81, as shown in Figure 4, and under the tamping foot 15^c of the mat packing arm 15. These address mats, as they are fed under the tamping foot 15^c, engage 30 a stop 15^a which precludes them from being advanced beyond the point of registration with the opening of the lower receptacle 13. When the tamping foot 15^c moves downwardly, it will engage the upper face 35 of the mat immediately thereunder and force said mat into the lower receptacle 13, which is provided with two spaced guide ways 22, as shown in Figure 2, which engage the notches 103 and 104 formed upon 40 the mat. The mats received in receptacle 13 are precluded from being ejected therefrom adjacent to the tamping foot 15^c by reason of the springs 21 and, in this manner, the mats accumulated in the receptacle 45 13 are prevented from expanding backwardly. The address mats received in the receptacle 13 are fed by the curved guide ways 22 into the usual galleys or trays, not shown.

50 As hereinbefore explained, those mats which it is desired to segregate from the quantity of mats ejected from the addressing machine, when positioned above the selector block 37, will receive the selecting pins 29 in the correspondingly positioned bosses 105, 106 and 107 which thereupon will permit of engagement between the electrical contact members 33^a of Figures 6 and 7. The electromagnet 34, on being energized, 55 will effect operative engagement between the cam members 45 and 16^a and, consequently, the tamping arm 15 will be drawn downwardly through the lever 48 and the link mechanism 51, to the position shown 60 in Figure 9. As such an address mat is

fed forwardly, it will be received on the top surface of the tamping foot 15^c and abut against a stop 15^a. When the tamping foot 15^c moves upwardly, the tamping arm 15 is released from the lever 48, as herein-after to be explained, and, consequently, the mat received on the upper surface of the tamping foot 15^c will be pushed into the upper receptacle 14.

As shown in Figure 4, the lower portion 75 of the receiver 14 is provided with two hinged, opposed and spaced dogs 52 that have inclined faces 52^a. The mats received on the upper face of the tamping foot 15^c are, therefore, forced upwardly between the two dogs 52 and precluded from moving backwardly by reason of springs 110 that are constantly pressing against the hinged dogs 52. The mats which it is desired to segregate are, therefore, supported upon the 80 teeth of the dogs 52 and, as they accumulate, are threaded upon the galley 22 of Figure 5. As shown in Figures 1 and 9, the galley 22 of the upper receptacle 14 is removably held therein by means of springs 68 which are secured to angle irons 67 that serve as a supporting structure of the upper receptacle 14. The upper receptacle 14 is supported upon a bracket 13^a by means of 85 screw bolts 69.

The lever 33 of Figure 6 is actuated by 90 means of the cam 53 during each revolution of the main driving shaft 28. As a result, the contact actuating member 32, during each revolution of the shaft 28, moves downwardly in order to break the electric circuit between the opposed electrical contact members 33. The relative position of the cam 53 is so determined that immediately 95 after an addressing printing mat has been received on the upper surface of the tamping foot 15^c, the electrical circuit through the electromagnet 34 is disrupted and, consequently, the tamping foot 15^c may partake 100 of its full upward range of movement thereby forcing the printing address mat representing the expiring subscription into the upper receptacle 14. By referring to Figure 10, it will be readily apparent how the tamping foot 15^c may force address mats into 110 the upper receptacle 14.

The cam members 16^a and 45 will continue 115 in engagement as long as the spring-pressed pin 43 is received in the recess 44. To withdraw this spring-pressed pin 43, the clutch 120 block 40 is provided with an inclined surface 57 (Figure 2) which is designed to cooperate with an inclined surface 56 formed on an extension 56^a, Figure 8, that is comprised in the spring-pressed pin 43. As the cam 45 rotates the inclined surface 56 of the pin 43 will effect engagement with the surface 57 formed on the clutch block 40 of the lever 36 and, therefore, as the cam 45 continues to revolve, will accordingly oppose 125

the action of the spring 42 and force the pin 43 out of the recess 44 into the position shown in Figures 2 and 8. Of course, the pin 43 will occupy the position shown in Figures 2 and 8 as long as the came 45 is stationary and the clutch block 40 is received in the annular recess 55. Immediately upon withdrawal of the clutch block 40, from the annular recess 55, which is occasioned when 5 the electromagnet 34 is energized, the spring-pressed pin 43 will be released and, as a consequence, effect engagement between the cam members 16^a and 45. It will be observed, however, that the clutch block 40 is 10 withdrawn from the annular recess 55 only when the electromagnet 34 is energized, thus attracting the armature 35, secured at the lower end of the lever 36, as shown in Figure 9.

When the cam members 45 and 16^a are 15 operatively connected through the agency of the pin 43, the friction brake 58 is incapable of holding the cam member 45 against rotation but, as soon as the electromagnet 34 is deenergized and the clutch block 40 is 20 received again in the annular recess 55, the two cams will become disengaged and, under this circumstance, the friction brake 28 will then hold the cam 45 against further 25 rotation.

The tension spring 54 which is attached to the lever 36 serves to positively hold the clutch block 40 in the annular recess 55. The tension spring 61 is connected at 62 to 30 the lever 18 and at 63 to the end 50 of the lever 48. The tension of the spring 61, as shown in Figure 1, serves to hold the lever arm 48 in such a position that the link 51 is either in alinement with, or just to the 35 rear of, a center line extending between the pivot 49 of the lever 48 and the pivotal connection 51^a between the link 51 and the packing arm 15. The position of the lever 48 may be adjusted by means of a stop screw 40 44 held in the lug 65 which is mounted upon the lever 18. The range of oscillation of the tamping arm 15 may, therefore, be controlled by adjusting the stop screw 64, since 45 this controls the relative position between 50 the lever 48 and the lever 18.

From the foregoing description of my 55 present invention, it will be apparent that my mechanism is adapted to be used in conjunction with addressing or mailing machines of any of the usual forms. The address printing plates or address mats as they 60 are ejected from the addressing machine are received by my selector mechanism and through distinctive markings formed on the address mats are selected in such manner 65 that those address mats representing expiring subscriptions are segregated and collected within the upper receptacle 14 while the other address mats are collected in the lower receptacle 13.

While I have described in detail one specific embodiment of my invention, it is obvious that many changes may be made in the form, construction and arrangement of the parts without departing from the spirit 70 and scope of the appended claims.

What I claim as new and desire to secure by Letters Patent of the United States is:—

1. An attachment for a printing machine employing address mats, said attachment 75 comprising a selector to which the address mats are delivered from said printing machine, electric circuit connections that are energized by said selector when it responds to predetermined distinguishing characteristics of said address mats, two receiving receptacles for the address mats, a common actuator that is adapted to operate intermediate said receiving receptacles, said actuator permitting the delivery of address mats 80 not possessing said predetermined distinguishing characteristics to one of said receptacles, and electrical means energized by said electric circuit connections for controlling the proper response of said actuator 85 in accord with said predetermined distinguishing characteristics of the address mats whereby said address mats are delivered to the other of said receiving receptacles.

2. An attachment for a printing machine 90 employing address mats, said attachment comprising a selector to which the address mats are delivered from said printing machine, electric circuit connections that are energized by said selector when it responds to predetermined distinguishing characteristics of said address mats, two aligned receiving receptacles for the address mats, a common actuator that is adapted to operate intermediate said receiving receptacles and 100 to engage each address mat delivered from said selector, said actuator forcing the address mats to one or the other of said receiving receptacles, and electrical means controlled by said selector and the associated 105 electric circuit connections for controlling the action of said actuator whereby address mats possessing said predetermined distinguishing characteristics will be forced into 110 one of said receiving receptacles.

3. An attachment for a printing machine employing address mats provided with distinctive markings, said attachment comprising a selector which operatively responds to address mats having predetermined distinctive markings, a plurality of receptacles to receive address mats, a common actuator engaging each address mat delivered from said selector and delivering it to one of said receptacles, said actuator delivering address mats not possessing the predetermined distinguishing characteristics to a predetermined receptacle, and electrically controlling means actuated by the operative response of said selector to address mats possessing the 120 125 130

- predetermined distinguishing characteristics for controlling the said actuator whereby all of such address mats will be selectively delivered to another one of said receptacles.
5. An attachment for a printing machine employing address mats provided with distinctive markings, said attachment comprising a selector which operatively responds to address mats having predetermined distinctive markings, electric circuit connections energized by said selector when it responds as aforesaid, a plurality of receptacles to receive the address mats, a common actuator engaging each address mat delivered from said selector and for delivering said address mats to any one of said receptacles, said actuator normally delivering address mats to a predetermined one of said receptacles, and electrically controlled means actuated by the operative response of said selector for controlling said actuator whereby address mats having the predetermined distinctive markings may be selectively delivered by said actuator to another one of said receiving receptacles.
5. An attachment for a printing machine employing printing mats, said attachment being operable on the printing mats delivered from printing position of said printing machine and comprising a selector that separately engages each of said printing mats as it is discharged from the printing machine, electric circuit connections, that are energized by said selector when it responds to predetermined distinguishing characteristics of said address mats, a plurality of receptacles to receive said printing mats, a common actuator intermediate between said receptacles and engaging each of said address mats for delivering them to the said receptacles, said actuator delivering address mats not possessing the predetermined distinguishing characteristics to one of said receptacles, and electrically operated means controlled by said selector and controlling said actuator when printing mats possessing said predetermined distinguishing characteristics are engaged by said selector whereby said printing mats of predetermined distinguishing characteristics are delivered to the same one of said receptacles.
6. An attachment for a printing machine employing printing mats, said attachment being operable on the printing mats delivered from printing position in said printing machine and comprising a selector that separately engages each printing mat as it is discharged from the printing machine, a plurality of receptacles to receive said printing mats, a common actuator for delivering printing mats to any one of said receptacles, said actuator normally delivering printing mats to one of said receptacles, and electrically controlled means operated by said selector for controlling the movement of said actuator, said means being operated when printing mats of predetermined characteristics are engaged by said selector in order that said actuator may deliver all printing mats possessing said predetermined characteristics to another one of said receptacles.
7. An attachment for a printing machine employing printing mats, said attachment being operable on the printing mats delivered from printing position in said printing machine and comprising a selector that separately engages said printing mats as they are discharged from the printing machine to detect the pre-determined classification thereof, a plurality of receptacles to receive said printing mats, a common actuator to deliver said printing mats to either one of said receptacles after said printing mats are disengaged from the selector, and electrically controlled means actuated by said selector which operates when printing mats of a certain predetermined classification are engaged by said selector for operating said actuator whereby such printing mats may be selectively delivered to some one of said receptacles.
8. An attachment for a printing machine employing printing mats, said attachment being operable on the printing mats delivered from printing position in said printing machine and comprising a selector separately engaging said printing mats as they are discharged from the printing machine whereby mats of predetermined classification may be detected, superposed receptacles to receive respectively different classes of said printing mats, a common actuator to deliver address mats to any one of said receptacles, and electrical means controlled by said selector for controlling said common actuator whereby address mats of predetermined classification may be deposited into one of said receptacles.
9. An attachment for a printing machine employing printing mats that is operable on the printing mats subsequent to their delivery from printing position in said printing machine, and which comprises a selector separately engaging said printing mats as they are discharged from the printing machine, two superposed receptacles to receive said printing mats, an oscillating packing arm intermediate said receptacles and adapted to deposit said printing mats in said receptacles, means for continuously oscillating said packing arm, and means controlled by said selector for varying the movement of said packing arm whereby the printing mats may be selectively deposited in either one of said receptacles.
10. An attachment for a printing machine employing printing mats that is operable upon the printing mats delivered from printing position in said printing machine and which comprises a selector separately en-

gaging said printing mats as they are discharged from the printing machine, two superposed receptacles to receive said printing mats, a continuously oscillating actuator 5 intermediate said receptacles and normally adapted to deposit the said printing mats in one of said receptacles, and means controlled by said selector for varying the normal movement of said actuator whereby printing 10 mats of certain predetermined characteristics may be deposited in the other of said receptacles.

11. An attachment for a printing machine employing printing mats that is operable 15 upon the printing mats delivered from printing position in said printing machine and which comprises a selector separately engaging said printing mats as they are discharged from the printing machine, two 20 superposed receptacles to receive said printing mats, an actuator intermediate said receptacles and normally adapted to engage on its lower surface said printing mats as they are delivered from said selector, and 25 means controlled by said selector for varying the normal movement of said actuator whereby printing mats having certain predetermined characteristics may be received

on its upper face in order that such printing mats may be selectively deposited in the 30 upper one of said receptacles.

12. An attachment for a printing machine employing address mats, said attachment comprising a selector to which the address mats are severally delivered from said printing machine, electric circuit connections energized by said selector when it responds to predetermined distinguishing characteristics possessed of certain of said address mats, two receiving receptacles for the mats, a 35 common actuator that is adapted to operate intermediate said receiving receptacles and to engage each address mat delivered from said selector thereby forcing it into one or the other of said receiving receptacles, and 40 means controlled by said electric circuit connections for permitting said actuator to be positioned selectively with reference to said mats whereby all mats possessing the predetermined distinguishing characteristics are 45 inserted into the same one of said receiving receptacles.

In witness whereof, I have hereunto subscribed my name.

JOHN E. JOHNSON.

CERTIFICATE OF CORRECTION.

Patent No. 1,675,710.

Granted July 3, 1928, to

JOHN E. JOHNSON.

It is hereby certified that error appears in the printed specification of the above numbered patent requiring correction as follows: Page 5, line 128, claim 3, for the word "controlling" read "controlled"; and that said Letters Patent should be read with this correction therein that the same may conform to the record of the case in the Patent Office.

Signed and sealed this 7th day of August, A. D. 1928.

(Seal)

**M. J. Moore,
Acting Commissioner of Patents.**
